(57) **CLAIM**

The ornamental design for a remote control docking cradle, as shown and described.

DESCRIPTION

FIG. 1 is a perspective view of a remote control docking cradle illustrating our new design;

FIG. 2 is a perspective bottom view thereof;

FIG. 3 is a front view thereof;

FIG. 4 is a rear view thereof;

FIG. 5 is a side view thereof;

FIG. 6 is a top view thereof;

FIG. 7 is a bottom view thereof; and,

FIG. 8 is a perspective view of the remote control docking cradle having a remote control illustrated in a dashed-line format to show one exemplary use thereof.

It will be understood that the dashed lines presented in the drawings are for illustration purposes only and do not form any portion of the claimed design.
